Nelson M. Howard

UNITED STATES PATENT OFFICE.

HARRY D. HAMILTON, OF WINTHROP, MASSACHUSETTS, ASSIGNOR TO UNITED SHOE MACHINERY CORPORATION, OF BOSTON, MASSACHUSETTS, A CORPORATION OF NEW JERSEY.

PACKAGING OF ARTICLES.

1,330,864.

Specification of Letters Patent.

Patented Feb. 17, 1920.

Application filed May 21, 1919. Serial No. 298,660.

To all whom it may concern:

Be it known that I, HARRY D. HAMILTON, a citizen of the United States, residing at Winthrop, in the county of Suffolk and 5 State of Massachusetts, have invented certain Improvements in the Packaging of Articles, of which the following description, in connection with the accompanying drawings, is a specification, like reference characters 10 on the drawings indicating like parts in the several figures.

The present invention relates to the packaging of articles. For the purpose of illustration the invention is herein set forth 15 with particular reference to its application to the packaging of articles such as rubber heels in individual pairs ready for attachment to shoes.

Rubber heels are usually provided with a 20 plurality of partially or entirely formed nail holes to facilitate the attachment of the heels to the shoes and the required number of attaching devices, usually nails, are ordinarily included with each pair of heels, the 25 nails being placed commonly in a separate envelop in the container for each pair of heels.

The present invention has for an object to 30 improve the packaging of rubber heels to the end that the heels may be packaged together with their attaching devices more economically and carefully and received by the user with the attaching devices already assembled with each of the heels and in 35 proper numbers and dispositions for the user to attach the heels most conveniently and accurately.

With this object in view the invention 40 provides a heel package comprising a pair of heels provided with nail receiving openings in one face of the heel and having heel attaching nails inserted in said openings and projecting outwardly beyond said face of the heel, the heels being arranged to cause 45 the projecting parts of the nails of the two heels to extend oppositely between the heels, and means formed and arranged to hold the heels so positioned to prevent dislodgment of the nails. As herein illustrated, the 50 attaching devices comprise a plurality of nails, the shanks of which are inserted in the partially formed holes in the heels and the heels are relatively positioned to cause each heel of the pair to serve as an abutment for the 55 attaching devices carried by the other heel

whereby the heels co-act to prevent dislodgment of the nails. The heels so prepared are then provided with means for holding the heels in relative position, the illustrated means being a paper box.

As a result of so packaging rubber heels, more care will be exercised in furnishing the required number of nails for the attachment of the heel by the user than where they are separately furnished and when the 60 heels are to be attached to the shoes the nails will be all ready in proper locations for driving without the exercise of skill, the loss of time and inconvenience heretofore incident to the handling and locating of the 65 nails in the heels. In the types of rubber heels wherein washers are embedded in the 70 heels, for the purpose of co-acting with the head of the attaching nail, the nails are preferably inserted a sufficient distance into 75 the heels for their points to project through the washers with the result that the accurate driving of the nails by the user is assured.

Other objects and novel characteristics of the present invention will now be described 80 in connection with the accompanying drawings illustrating a preferred embodiment of the invention and the invention will then be defined in the appended claims.

The drawing illustrates in perspective 85 view, and partly in section, a pair of heels packaged according to a preferred embodiment of the present invention.

The heels 2, which may be of any of the usual types, are molded with a plurality of 90 holes or apertures 4 by which the heels are to be attached to the shoe, the attaching devices 6 herein illustrated being nails. The requisite number of nails 6 to attach the heels are mounted in the heels 2 by having the shanks 95 or pointed ends of the nails 6 inserted in the holes or apertures 4. In the heels illustrated, washers 8 are embedded midway between the tread surfaces 10 and the heel seat surfaces 12 of the heel and preferably located at the termination of the holes 4 and the nails 6 are inserted in the holes 4 so that their points project slightly through the washers but not far enough for the points to project through the surface 12 of the heel. 100 In this way the points of the nails 6 are lightly held frictionally by the material constituting the heels and ordinarily the holes 4 are sufficiently small for the walls of the holes also to engage the shank of the nail. 105 110

The head portions of the nails 6, as shown, project from the surface 10 of the heel.

When each heel of the pair has been provided with the nails as described, the two 5 heels of the pair are placed in parallel relationship with the heads 14 of the nails 6 of each heel projecting so as to bear against or abutting the tread face 10 of the other heel of the pair and the two heels are then confined in this relationship in some suitable manner, as by slipping them into a box or carton 10 as illustrated.

With the two heels packaged as thus described, the attaching devices or nails 6 are 15 prevented from escaping from their mounted positions in the heels and when the package is opened the user finds the nails not only accurate as to number but also properly conditioned and positioned for driving. The 20 advantage resulting from the attaching devices being frictionally held is that when the user opens the package and separates the two heels from each other the attaching devices are maintained in their driving positions 25 in the heel while the heel is being placed in position to be attached to the boot or shoe.

While the invention has been herein illustrated in connection with a certain type of heel and the term "rubber" used to describe 30 the heel, it is to be understood that neither the type of heel illustrated nor the term "rubber" is to be construed as a limitation. Moreover, while a common form of carton has been illustrated for a container for the 35 pair of heels, it is to be understood that I do not limit myself thereto but may employ any equivalent means for holding the heel assembled in such relative positions that the attaching devices mounted therein can not 40 escape from their mounted positions.

Having thus described my invention, what I claim as new and desire to secure by Letters Patent of the United States is:

1. A heel package comprising a pair of 45 heels provided with nail receiving openings in one face of the heel and having heel attaching nails inserted in said openings and

projecting outwardly beyond said face of the heel, the heels being arranged to cause the projecting parts of the nails of the two 50 heels to extend oppositely between the heels, and means formed and arranged to hold the heels so positioned to prevent dislodgment of the nails.

2. A heel package comprising a container 55 and a pair of heels in said container, each of said heels being provided with nail receiving openings in one face of the heel and having heel attaching nails inserted in said openings and projecting outwardly beyond 60 said face of the heel, the heels being arranged to cause the projecting parts of the nails of the two heels to extend oppositely between the heels, and the container being 65 formed and arranged to hold the heels so positioned to prevent dislodgment of the nails.

3. A heel package comprising a pair of 70 heels provided with nail receiving openings in one face of the heel, and having heel attaching nails partially inserted in said openings in position to be driven, the heels being arranged to cause the projecting parts of the 75 nails of the two heels to extend oppositely between the heels, and means formed and arranged to hold the heels so positioned to prevent dislodgment of the nails from the heels during transportation of the heels.

4. That improvement in methods of packaging heels which consists in providing 80 each of a pair of heels with nail receiving openings in one face of the heel, inserting 85 nails in said openings with a portion of each nail projecting from the tread surface of the heel, positioning the pair of heels so that the projecting parts of the nails of the two heels extend oppositely between the heels and abut 90 against the opposite tread faces of the heels, and then applying means to maintain the two heels in said position and prevent dislodgment of the nails.

In testimony whereof I have signed my name to this specification.

HARRY D. HAMILTON.
